United States Patent Office

Des. 204,405
Patented Apr. 12, 1966

204,405

CLOCK

Mel Appel, Livingston, and Martin Schnur, West Orange,
N.J., assignors to General Time Corporation, New
York, N.Y., a corporation of Delaware

Filed July 19, 1965, Ser. No. 86,193

Term of patent 14 years

(Cl. D42—7)

FIG. I

FIG.2

Des 204,405

PAGE 3

FIG.3

FIG. 4

FIG. 1 is a front elevational view of a clock showing our new design;

FIG. 2 is a rear elevational view thereof;

FIG. 3 is a top plan view thereof; and

FIG. 4 is a right side elevational view thereof, the left side being a mirror image thereof.

We claim:

The ornamental design of a clock, substantially as shown.
